UNITED STATES PATENT OFFICE.

JOSHUA ROBINSON, OF LAWRENCE, MASSACHUSETTS.

SHUTTLE.

No. 854,531.

Specification of Letters Patent.

Patented May 21, 1907.

Application filed January 11, 1907. Serial No. 351,749.

To all whom it may concern:

Be it known that I, JOSHUA ROBINSON, of Lawrence, county of Essex, State of Massachusetts, have invented an Improvement in Shuttles, of which the following description, in connection with the accompanying drawings, is a specification, like characters on the drawings representing like parts.

This invention relates more particularly to that class of shuttles which are employed in worsted weaving looms, in which a spindle, having a flanged extremity, is adapted to be removably connected to a socket piece pivoted in the shuttle, so that the bobbin may be passed on and off the base end of the spindle by removing the latter from its socket.

It is desirable to employ shuttles adapted to receive bobbins capable of carrying as much thread as possible, and, for this reason, the shuttles are made to carry bobbins of the greatest length practicable. It will be obvious that a slight looseness or yielding of the spindle at its base end, or of the socket, will permit movement to a much greater extent at the tip of the spindle. The spindle and socket often become worn so that the spindle becomes more or less loose in its socket, and this looseness is often sufficient to permit the spindle to swing laterally or horizontally to a sufficient extent to permit the edge of the flange on the end of the spindle to strike the inner sides of the shuttle, with the result that the thread is frequently caught therebetween and broken.

The socket piece is, or should be held to swing closely between the sides of the recess in the shuttle body in which it is placed, so that any tendency of the socket to swing laterally or horizontally to a material extent will be prevented. It frequently happens, however, that the socket piece does not fit the sides of its recess as tightly as it should when the shuttle is new, and also that the wood becomes worn away to such an extent that it is of no assistance in preventing transverse swinging movement of the socket piece and the spindle.

The object of my invention is to provide means whereby the spindle is so held that all tendency thereof to become loose in the socket and to swing laterally therein is prevented, and, further, to provide means whereby the lateral swinging of the socket is also prevented. I accomplish these objects by

the means shown in the accompanying drawing, in which,

Figure 1 is a plan view of the portion of the shuttle provided with my invention. Fig. 2 is a central longitudinal sectional view on the line 2—2 Fig. 1. Fig. 3 is an enlarged view of the shuttle socket. Fig. 4 is a sectional view on the line 4—4 of Fig. 2. Fig. 5 is an enlarged detail view of the end of the base spindle.

As shown in the drawing, the shuttle body *a* is provided with a socket piece *b* which is pivoted on the pin *c* mounted in the shuttle body, the usual holding spring *d* being provided. The spindle *e* is provided with the usual holding flange at its tip and recesses in its base end to receive the usual fixed locking pins *f* and *g* mounted in the shuttle body for locking the spindle in place when turned into its normal position in the shuttle.

The base end of the spindle, which is fitted in the socket, is centrally and vertically slotted from its end to a point adjacent or a short distance beyond the end of the socket to provide two oppositely disposed, semi-cylindrical arms *e'*, *e''*, said arms being adapted to spring apart horizontally and to be pressed together to an extent sufficient to permit them to be inserted in the socket, the end of said arms being slightly tapered to permit this to be accomplished readily. The extent to which and the force with which these arms are adapted to spring apart is designed to be sufficient to cause them to engage the inner opposite sides of the socket with sufficient force to hold the spindle from swinging horizontally or laterally therein.

The socket *b* is also split from its front end to a point a short distance in advance of its pivot pin *c* providing two sections *b'* and *b''*, which are adapted to be sprung apart horizontally, so that the outer sides thereof will fit closely in the shuttle body recess in which said socket is located. A tapered plug or screw *g* is provided in the flange of the socket against which the base of the bobbin rests, said plug being adapted to be forced downwardly or inwardly to force said sections *b'*, *b''* apart, so that in case the socket does not fit snugly in the shuttle body or the body becomes worn, so that the socket fits loosely therein and a lateral motion thereof is permitted, such lateral motion may be prevented by simply forcing the tapering screw or

plug g' inwardly sufficient to spread the end portion of the socket until it fits the recess in which it is located. In case such adjustment is made, it will be necessary to spread 5 the spring arms e' , e^2 of the spindle correspondingly, otherwise the spindle would fit loosely within the socket. As the pivoted end of the socket is not spread it will be necessary, in such instance, to bend out the inner 10 intermediate portion of said arms without spreading the end portions to such an extent as to interfere with the facility with which the spindle may be inserted in the socket. With the above described construction, 15 therefore, the spring arms e' , e^2 will hold the spindle from transverse swinging movement in the socket, and the socket may be adjusted to the recess in which it is located so that it cannot swing transversely of its pivot, there- 20 by preventing the breaking of the thread by the engagement of the spindle with the inner sides of the shuttle.

Having thus described my invention, what I claim as new and desire to secure by Letters Patent is:—

1. A shuttle of the character described comprising a pivotally mounted socket piece, and a spindle adapted to be inserted and locked therein, the end portion of said spindle located in the socket comprising a pair of spring arms adapted to fit in the socket and to engage opposite sides thereof to hold the spindle from horizontal or transverse swinging movement in the shuttle, substantially as 35 described.

2. A shuttle of the character described comprising a pivotally mounted socket piece

and a spindle having its base end portion adapted to be inserted in said socket the base end portion of said spindle being composed 4c of two oppositely disposed, semi-cylindrical arms fitted in said socket, and acting yield- 45 ingly to engage opposite sides of the socket to hold the spindle from transverse swinging movement therein, substantially as de- scribed.

3. A shuttle of the character described comprising a body having a recess, a socket piece pivotally mounted at one end in said recess, and having its opposite end portion 5c composed of two sections, means for spreading said sections to fit the sides of said recess, and a spindle adapted to be inserted in said socket piece having its insertible portion composed of two arms adapted to be spread 55 to fit the socket, substantially as described.

4. A shuttle of the character described comprising a body having a recess, a socket piece pivotally mounted at one end in said recess, and having its opposite end portion 60 composed of two sections adapted to be spread to fit the sides of said recess, and a spindle adapted to be inserted in said socket piece having its insertable portion composed of two arms adapted to be spread to fit the 65 socket, substantially as described.

In testimony whereof, I have signed my name to this specification, in the presence of two subscribing witnesses.

JOSHUA ROBINSON.
